UNITED STATES PATENT OFFICE

HARVEY HURRELL, JR., OF BRIDGEPORT, CONNECTICUT

COMBINATION ELECTRIC FAN AND FIXTURE

Application filed August 17, 1928. Serial No. 300,385.

This invention relates to a combination electric fan and fixture for ventilating and illuminating cars, such as railway Pullman cars and elevator cars. It has for an object 5 to provide an improved fixture which will combine a ventilating fan and lighting device in one structure which may be mounted in position with a single mounting means.

It is also an object of the invention to provide a device which will have an improved 10 ventilating effect, and in which the ventilator will also act as a cooling means for the lighting device as well as for the operating means of the ventilator.

15 With the foregoing and other objects in view, the invention consists in certain novel features of construction, combinations and arrangements of parts as will be more fully described in connection with the accompanying drawings.

In these drawings,

Fig. 1 is a transverse diagrammatical section of the upper portion of a Pullman car showing my improved combination fixture applied thereto, the fixture being shown in 25 elevation except for certain parts which are broken away to more clearly show the construction.

Fig. 2 is a horizontal section looking toward the bottom of Fig. 1, the section being substantially on line 2—2 of Fig. 1.

Fig. 3 is a detail section on an enlarged scale of one side portion of the device.

Fig. 4 is a transverse section substantially on line 4—4 of Fig. 1.

Fig. 5 is a detail, partly in side elevation and partly in section showing the mounting and ventilating feature of the motor.

Fig. 6 is a vertical section of the upper portion of an elevator car showing my improved device applied thereto, and

Fig. 7 is a horizontal section looking toward the bottom of Fig. 6, the section being substantially on line 7—7 of Fig. 6.

45 Referring to Figs. 1 to 5 the side walls and ceiling of a Pullman car are shown diagrammatically at 10 and 11 respectively, with ventilating openings 12 in the side walls for admission of air, the details of construction 50 of the car, screens and so forth for these

ventilating openings are not shown as they form no part of my invention. My improved combination of ventilating and lighting fixture comprises a substantially conical base and deflector 13 above which is mounted a 55 fan 14 arranged to force air downwardly to the surface of the deflector, as indicated by the arrows in Fig. 1, so that this air is forced laterally and downwardly in all directions to ventilate all portions of the interior of the 60 car and to widely diffuse the stream of moving air so that it will not be concentrated in any one direction to cause inconvenience or discomfort to any passenger. The fan is operated by a motor 15 mounted within the 65 deflector 13 which motor is operated by any means usually an electric motor from any suitable source of electric current, indicated at 16, and controlled by any suitable switch, not shown. The deflector 13 is open at its 70 lower side and has an inwardly extending flange 17 by which it is mounted on the supports 18. This support comprises a plurality of depending elements secured to the ceiling of the car and extending radially inwardly under the deflector 13 and secured to a common central element 19. The flange 17 rests upon these supports and is secured thereto by any suitable means, such as the bolts 20.

The upper end of the deflector 13 is also 80 open for admission of air from the fan for ventilating and cooling the motor 15. This opening is indicated at 21 and may be surrounded by an inwardly extending flange 22 to the inner and lower side of which are secured the depending supports 23 which may be secured to the flange by any suitable means, such as the screws 24. The motor may be mounted on these depending supports by any suitable means, it being preferred to extend 85 the lower end of the members 23 under the lower end of the motor housing, as shown at 25. This housing has a series of inlet openings 26 at its upper end with similar outlet openings 27 at its lower end so that air passing inwardly through the openings 21 will flow downwardly through the motor housing, as shown by the arrows in Fig. 5, and prevent 90 overheating of the armature and coils. The 95 100

air issues from the motor housing into the interior of the deflector 13.

My improved combination fixture also includes a dome light which is mounted below the deflector 13 and the supporting means 18.

5 The base and reflector 28 is mounted at the lower side of the deflector and the support 18 and is enclosed within a ring base 29, these elements being secured to the support by the bolts 20, and therefore, these bolts mount both 10 the ventilating device and the dome light on the supports 18. This is the preferred construction, although separate means may be employed for securing the dome light to the 15 support from that employed for the ventilating device. The dome structure may include the usual swinging glass dome 30 hinged to the base ring 29 at 31 and detachably secured thereto at its opposite edge by any 20 suitable means, as a screw 32, to permit the dome to be dropped down to give access to the lamp 33. This arrangement gives a very compact, neat and attractive construction which has the combined features of ventilating 25 the car and also illuminating it. The air which flows through the motor into the deflector 13 passes out through the slot 34 between the base 28—29 of the dome light and the base of the deflector 13, the slot being provided 30 by the spacing of these elements by the supporting elements 18. Air, therefore, flows over the base and reflector 28 and prevents overheating of the same.

In Figs. 6 and 7, I have shown the device 35 as applied to the ceiling of an elevator car. Here the walls of the car are shown diagrammatically at 35 and the ceiling has an opening 36 therein. Mounted in this opening are the supporting elements 38 corresponding to the 40 supporting elements 18 shown in Figs. 1 and 5. They are secured to the ceiling of the car, extend radially inward and are attached to the central element 39 to give a more rigid construction. The ventilating and dome 45 light construction is the same as that shown in Figs. 1 to 5, the deflector 13 of the fan being mounted on top of the supports 38 the same as in the first form and the dome light being mounted on the lower side of these supports 50 the same as in the first form. The space between this fixture and the sides of the opening 36 may be covered with a suitable screen 40. This ventilating and lighting device operates the same in this arrangement as in the first 55 form, the fan forcing air downwardly against the deflector 13 by which it is deflected downwardly and laterally in all directions through the screen 40 into the car to ventilate the same, while the dome light provides the necessary 60 illumination.

It will be obvious from the foregoing description that I have devised an improved combination ventilating and lighting fixture which may be assembled, sold and installed 65 as a unitary structure, has a neat and attrac-

tive appearance, provides ventilation for all parts of the interior of a car without concentrating a stream of air in any given direction, and therefore, will not cause any discomfort to the occupants of the car, and the flow of air 70 prevents overheating of the motor and the elements of the lighting fixture.

Having thus set forth the nature of my invention, what I claim is:

1. In a device of the character described, a 75 substantially cone shaped deflector, a fan above said deflector arranged to blow air downwardly against the surface thereof, a motor for operating the fan, a base for a dome light mounted below said deflector, a 80 support for mounting the deflector and base adjacent the ceiling of a car, and means for securing the deflector and base to the support.

2. In a ventilating and lighting fixture of 85 the character described, a substantially conical deflector, a motor mounted within the deflector, a fan above the deflector operated by the motor and arranged to force air downwardly against the deflector, a support for 90 the deflector capable of mounting it from the top of a car and extending below the lower end of the deflector, a dome light mounted on the lower side of the support, and common means for securing the deflector and said 95 dome light to the support.

3. In a ventilating and lighting fixture of 100 the character described, a substantially conical deflector, a motor mounted within the deflector, a fan above the deflector operated 105 by the motor and arranged to force air downwardly against the deflector, said deflector being provided with an opening at its upper end for entrance of air from the fan to the interior of the deflector, a dome light 110 having a base mounted below the deflector, and a support for the deflector and the dome light extending between them and holding them in spaced relation for exit of the air from the interior of the deflector.

4. In a ventilating and lighting fixture of 115 the character described, a substantially conical deflector, a motor mounted within the deflector, a fan above the deflector operated by the motor and arranged to force air downwardly against the deflector, said deflector being provided with an opening in its upper end for entrance of air from the fan, the motor being mounted in alignment with said opening and having passages through its 120 housing for the air, a dome light having a base including a reflector mounted below the deflector, a support capable of being secured to the ceiling of a car and extending between the deflector and reflector to hold them in 125 spaced relation to form an exit for air from the interior of the deflector, and means for securing the deflector and the base to the support.

5. In a ventilating and lighting fixture of 130

the character described, a support capable of being secured to the ceiling of a car and depending therefrom, a substantially conical deflector carried by the support, a fan above the deflector mounted to rotate in a horizontal plane and force air downwardly against the deflector, a motor for operating the fan mounted within the deflector, and a dome light also carried by said support and mounted at the under side of the base of the deflector.

In testimony whereof I affix my signature.
HARVEY HUBBELL, JR.
